UNITED STATES PATENT OFFICE

157,506

CONSOLE FOR A COMPUTING MACHINE

George H. Kress, Vestal, N. Y., and Carl W. Sundberg, Detroit, Mich., assignors to International Business Machines Corporation, New York, N. Y., a corporation of New York

Application June 16, 1948, Serial No. 146,997

Term of patent 14 years

(Cl. D64—11)

To all whom it may concern:

Be it known that we, George H. Kress and Carl W. Sundberg, both citizens of the United States of America, residing, respectively, at Vestal, in the county of Broome and State of New York, and at Detroit, in the county of Wayne and State of Michigan, have invented a new, original, and ornamental Design for a Console for a Computing Machine, of which the following is a specification, reference being had to the accompanying drawing, forming part thereof.

Fig. 1 is a front perspective view of a console for a computing machine, showing our new design;

Fig. 2 is a front elevational view; and

Fig. 3 is a right end elevational view of the same.

The portions indicated by oblique lines are to be finished by means of perforations as seen in the immediate areas.

We claim:

The ornamental design for a console for a computing machine, as shown and described.

GEORGE H. KRESS.
CARL W. SUNDBERG.
